[57] CLAIM

The ornamental design for a soap dispenser, substantially as shown and described.

DESCRIPTION

FIG. 1 is a top perspective view of a soap dispenser showing my new design;

FIG. 2 is a top plan view thereof;

FIG. 3 is a frontal elevational view thereof;

FIG. 4 is a side elevational view thereof taken from the right of FIG. 2, the opposite side being a mirror image thereof;

FIG. 5 is a bottom plan view thereof;

FIG. 6 is a rear end view thereof.
